UNITED STATES PATENT OFFICE

EDWARD B. ALLEN, OF NEWTOWN, CONNECTICUT, ASSIGNOR TO THE SINGER MANUFACTURING COMPANY, OF ELIZABETH, NEW JERSEY, A CORPORATION OF NEW JERSEY

THREAD-CUTTING MECHANISM FOR SEWING MACHINES

Application filed October 19, 1929. Serial No. 400,768.

This invention relates to thread-cutting mechanism for sewing machines, more particularly of the two-thread type, and has for an object to provide simplified means for severing the under-thread and holding the under-thread end for the formation of the initial stitches of the next sewing operation. A further object of the invention is to provide means for severing and holding the under-thread so that, in the finished product of the machine, the beginning and finishing ends of the under-thread of the stitched work will be of minimum length. Still further, the invention has for an object to provide an improved under-thread cutting and nipping mechanism particularly adapted for use in sewing machines of the well known Singer 71-Class, represented in the U. S. Patent to Allen, No. 885,310, of Apr. 21, 1908.

To the attainment of the ends in view, cooperating thread-cutting and -nipping blades are mounted in a fixed operating location or thread-cutting position at the underside of the throat-plate of the machine close to the needle-hole but slightly to one side thereof. Means are provided for bending or carrying the under-thread to one side sufficiently to bring it within range of the movable element or elements of the thread-cutter and -nipper for the thread-severing operation. Means are also provided for opening the thread-cutter and -nipper momentarily, after the initial stitches of the next sewing operation have been formed, to release the beginning end of the under-thread. A feature of the invention is the provision of means for opening and subsequently closing the thread-cutter and -nipper in one continuous movement of the thread-bender from retracted position to thread-cutting position, whereby the thread-cutter and -nipper is first opened to receive the approaching under-thread and is closed when the under-thread arrives at thread-cutting position. The above and other features of the invention will be hereinafter more fully described and particularly pointed out in the appended claims.

In the accompanying drawings Fig. 1 is a bottom plan view of the thread-cutting and -nipping mechanism, in its preferred embodiment,

ment, showing the thread-bender at thread-cutting position. Fig. 2 is a similar view showing the thread-bender in retracted position. Fig. 3 is a section on the line 3—3, Fig. 1. Fig. 4 is a section on the line 4—4, Fig. 1. Fig. 5 is a perspective view of the thread-cutter and -nipper. Fig. 6 is a section on the line 6—6, Fig. 1. Fig. 7 is a perspective view of the under-thread catcher or bender. Fig. 8 is a section on the line 8—8, Fig. 1. Fig. 9 is a complete bottom plan view of the machine shown in Fig. 1, and Fig. 10 is a view showing certain of the thread-cutter operating connections looking from the rear end toward the front end of the machine.

The machine is of the straight buttonhole sewing type and is constructed substantially in accordance with my application, Serial No. 400,767, filed herewith, and the following copending applications: E. B. Allen and W. Myers, Serial No. 272,416, filed Apr. 24, 1928; and E. B. Allen, Serial No. 367,511, filed May 31, 1929.

The machine comprises the usual flat bed 1 above which is the usual superstructure (not shown). The stitch-forming mechanism comprises the reciprocating and laterally jogging needle 2 and cooperating shuttle 3 which are driven as usual from the main-shaft *s*, Fig. 9, the period of operation of which is controlled by the usual stop-motion device 4. The shuttle includes the usual thread-case 3' for the mass of under-thread *t*.

The machine has a work-clamp 5, Fig. 9, which is mounted as usual on the longitudinal slide-plate 6 having movement lengthwise of the bed 1, in the cross slide-plate 7 which has movement transversely of the bed 1. Movements are imparted to the slide-plates 6 and 7 by the feed-wheel 8 having the longitudinal feed-cam 9 and lateral feed-cam 10 which move the work-clamp during the sewing operation to place the stitches in the desired order or arrangement.

The needle works through a hole 11 in the throat-plate 12; the hole 11 being in the form of a slot to accommodate the needle in its different positions of descent due to its lateral jogging movement. In sewing the final barring stitches of a straight buttonhole it is

customary in a machine of the present type to increase the amplitude of vibration of the needle, so that the needle will descend alternately in the positions 2 and 2'. In the present machine the follower nose 13 of the usual stop-motion tripping lever 14 is adjusted so that it will be engaged by the tripping point 15 on the feed-wheel 8 at the proper time to stop the machine with the needle out of the work at its position 2, rather than at its alternate position 2', so that the last stitch in the work will be made as closely as possible to the thread-cutter and -nipper to be described.

The thread-cutting and -nipping mechanism comprises spaced stationary cutter and nipper blades, 16 and 17, respectively, between which are pivoted at 18 the movable cutter and nipper blades, 19 and 20, respectively. The cutter-blade 19 has extending laterally therefrom an actuating arm 21 formed with a downturned lip 22 affording a striking face for engagement by the cutter-operating push-bars 23, 24. The movable nipper-blade 20 is pinned to the cutter-blade at 25 and moves with the latter. The thread-cutting and -nipping device, including the stationary blades, 16, 17 and movable blades, 19, 20, is mounted by screws 20' on the under side of the guide-rib element 7', Fig. 8, of the cross slide-plate 7 in a position close to the end of the needle-clearance slot 11 in the needle-throat member 12. The spring 26 connected to the arm 21 tends to move the blades 19, 20 to closed position between the stationary blades 16, 17 to cut and nip the bobbin-thread.

As the thread-cutter is positioned and has a range of action slightly to one side of the needle-path, it will not of itself catch the under-thread *t*. Means are therefore provided to carry the under-thread into the range of action of the thread-cutter. For this purpose there is pivoted at 27 on the cross slide-plate 7 a thread-engaging arm or thread-bender 28 the free end of which is formed with a horizontal slot 29, Figs. 7 and 8, providing top and bottom legs 30, 31 straddling the movable blades 19, 20 while the latter are in open position, as shown in Figs. 1 and 3. The legs 30, 31 are each formed in one edge with a thread-catching notch defining the thread-catching fingers 32, 33 which catch the bobbin-thread *t* and carry it between the open jaws of the thread-cutting and -nipping device, Figs. 1 and 4; the top and bottom fingers holding the thread more nearly at right angles to the plane of action of the movable blades 19, 20, than it would be held by one finger alone.

The arm 28 is actuated by a link-connection 34 with a slide-bar 35 from which depends a stud 36 embraced by the forked end 37 of a lever 38 fulcrumed at 39 below the bed 1 and at its other forked end 40 embracing a ball-stud 41 carried by the lower end of a lever 42

sustained by and free to turn relatively to the rock-shaft 43. The lever 42 carries a roller stud 44 which is engaged by the cam-shaped end 45 of an arm 46 fixed to the rod 47. When the rod 47 is projected downwardly by a pull 70 on the lever 48, also loose on the shaft 43, the cam-end 45 of the arm 46 swings the lever 28 across the lead of the bobbin-thread from the position shown in Fig. 2 to that shown in Fig. 1; whereby the bobbin-thread is caught by 75 the fingers 32, 33 and carried into the open jaws of the thread-cutter.

Slidably mounted on the underside of the cross slide-plate 7, between the guide-pins 49, 50, is the push-rod or latch 23 previously referred to which carries a stud-screw 51 passing through a slot 52 in the arm 28. The tail 53 of the latch is inclined to the left, Fig. 1, and is connected by a spring 54 to an arm 55 rigid with the cross slide-plate 7. The nose 56 of the latch 23 is inclined to the right and is adapted to engage the lip 22 of the thread-cutter arm 21 in its dotted line position, Fig. 2, and open the thread-cutter to its full line position, Fig. 1, (which has reached nearly its fully open position), during the thread-bending movement of the thread-catching arm 28. During the slight further and final movement of the arm 28, the inclined tail 53 of the latch 23 engages the guide-pin 49 and is deflected to the right, Fig. 1, thus swinging the latch about the guide-pin 50 as a fulcrum and disengaging its nose 56 from the lip 22, whereupon the spring 26 quickly swings the movable blades 19, 20 to closed or dotted line position, Fig. 1.

At the beginning of the next sewing operation and after the initial stitches have been formed, the nipped bobbin-thread *t*, Fig. 6, is released by movement of the push-bar 24 from the dotted line position shown in Fig. 2 to full line position, during which movement the push-bar 24 engages the lip 22 of the thread-cutter arm 21 and opens the nipper-blades. The push-bar 24 is formed at one end of the slide-bar 57 from which depends a stud 58 entering the slot 59 in one end of a lever 60 fulcrumed at 61 below the bed 1 and carrying an adjustable cam-follower nose 52 which is engaged by the nipper-opening cam 53 on the feed-wheel 8. The levers 60 and 38 have connected thereto the respective recovery springs 62 and 63.

Having thus set forth the nature of the invention, what I claim herein is:

1. In a two-thread sewing machine, the combination with a throat-plate having a needle-hole, of a thread-cutter and -nipper mounted below the throat-plate in thread-cutting and -nipping position spaced laterally of the needle-hole, and means for carrying the under-thread laterally to the thread-cutter and -nipper.

2. In a sewing machine, upper-thread mechanism, under-thread mechanism, a flat 130

5 bed, a throat-plate having a needle-hole, a thread-cutter and -nipper mounted below the throat-plate and including an element movable in a plane parallel to the plane of the sewing machine bed with a range of action at one side of and excluding the space directly below the needle-hole, and means for carrying the under-thread laterally into the range of action of the movable element of the thread-cutter and -nipper.

10 3. The combination with a thread-cutter having a member movable between open and closed positions, a spring for moving said member to closed position, a thread-bender movable from retracted to thread-cutting position for carrying the thread to be cut into the range of action of said movable member, and means connected to said thread-bender for opening and releasing said movable member in one continuous movement of the thread-bender from retracted to thread-cutting position.

15 4. In a two-thread sewing machine, the combination with a throat-plate having a needle-hole, of a thread-cutter and -nipper mounted below the throat-plate at one side of the needle-hole, a spring for closing the thread-cutter and -nipper, an under-thread bender, and means connected to the under-thread bender for opening and releasing the thread-cutter and -nipper in one continuous movement of the thread-bender in carrying the under-thread laterally to the thread-cutter and -nipper.

20 5. In a two-thread sewing machine, the combination of a throat-plate having a needle-hole, of a thread-cutter and -nipper mounted below said throat-plate at one side of the needle-hole and including a movable member, and a thread-bender arm having a hooked free end which is slotted to straddle the movable member of said thread-cutter and -nipper.

25 6. In a two-thread sewing machine, a needle, a throat-plate having a needle-hole, a spring-actuated thread-cutter element mounted below said throat-plate and having a range of action at one side of and in non-intersecting relation with the needle-path, an under-thread catcher movable laterally of the needle-path for carrying the under-thread into the range of action of the thread-cutter, and means for setting and releasing the thread-cutter during the thread-carrying movement of the thread-catcher.

30 7. In a two-thread sewing machine, the combination with a throat-plate having a needle-hole, of thread-cutting and -nipping means including relatively movable members mounted at the underside of the throat-plate with a range of action slightly to one side of the needle-hole, and means for engaging the under-thread and carrying it laterally to a position within the range of action of said relatively movable members.

35 8. The combination with a throat-plate having a needle-hole, of a thread-cutter and -nipper having cooperating fixed and movable jaws disposed below the throat-plate at one side of the needle-hole, an under-thread-bender, means actuated by said under-thread bender for opening said movable jaw, a spring for closing said movable jaw, and means for disengaging said jaw-opening means from the movable jaw.

40 9. In a sewing machine, the combination with a throat-plate having a needle-hole, of thread-cutting and -nipping means mounted below the throat-plate in a thread-cutting and -nipping position slightly to one side of the needle-hole and including a movable element having opening and closing movements, a spring for imparting the closing movement to said element, under-thread engaging means movable across the lead of the under-thread and toward said thread-cutting and -nipping means to carry the under-thread laterally to thread-cutting and -nipping position, and actuating means for imparting an opening movement to the movable element of the thread-cutting and -nipping means during the approach of the under-thread to thread-cutting and -nipping position, said actuating means releasing said movable element upon the arrival of the under-thread at thread-cutting and -nipping position.

45 10. The combination with a flat sewing machine bed, of a thread-cutter and thread-cutter-operating lever mounted below said bed, a thread-cutter-actuating lever fulcrumed above said bed and extending downwardly into engagement with said operating lever, a vertically disposed endwise movable actuating rod, and a cam on said rod connected to impart movement to said actuating lever.

50 11. In sewing machine thread-cutting mechanism, a spring-actuated thread-cutter, a thread-bender, and a latch actuated by said thread-bender for setting and releasing the thread-cutter in one continuous movement of said thread-bender.

55 12. Thread-cutting mechanism for sewing machines comprising, a movable spring-actuated thread-cutting element, a movable thread-bender element adapted to carry the thread to be cut to a position within the range of action of the thread-cutting element, means for actuating the thread-bender element, a latch actuated by the thread-bender element and adapted to engage and set the thread-cutter element, said latch having a cam-portion, and stationary means engaged by said cam-portion for disengaging said latch from said thread-cutting element to release the latter.

60 In testimony whereof, I have signed my name to this specification.
